(57) **CLAIM**

We claim the ornamental design for a drinking container, as shown.

DESCRIPTION

FIG. 1 is a top front perspective view of a drinking container showing our new design;

FIG. 2 is a front elevational view thereof;

FIG. 3 is a side elevational view thereof;

FIG. 4 is a top plan view thereof; and,

FIG. 5 is a bottom plan view thereof.

The broken lines in the drawings are for illustrative purposes only and form no part of the claimed design.
